UNITED STATES PATENT OFFICE.

HENRY C. NOFFSINGER, OF JEWELL, OHIO.

LUBRICATOR.

1,029,454.

Specification of Letters Patent. Patented June 11, 1912.

Application filed March 15, 1911. Serial No. 614,651.

To all whom it may concern:

Be it known that I, HENRY C. NOFFSINGER, a citizen of the United States, residing at Jewell, in the county of Defiance and State 5 of Ohio, have invented new and useful Improvements in Lubricators, of which the following is a specification.

- This invention relates to lubricators and particularly to one wherein the lubricant 10 will be fed by gravity to the object to be lubricated, the object of the invention being to provide an efficient dust-proof container for the lubricant and to provide in the discharge orifices of the container an absorbent 15 collector which will operate to collect dust or foreign matter and which will prevent the sediment in the bottom of the lubricant container from being discharged with the lubricant.
- 20 In the drawing, forming a portion of this specification and in which like numerals of reference indicate similar parts in the several views:—Figure 1 is a front view of the lubricator. Fig. 2 is a section on line 2—2 25 of Fig. 1. Fig. 3 is a longitudinal section on the line 3—3 of Fig. 1.

My improved lubricator comprises a lubricant container 1 which in the present instance is of rectangular configuration, being 30 provided in one of its vertical walls with an opening 2, the edges of the wall above and below the opening being formed U-shaped to provide longitudinal guide ribs 3 which fit in correspondingly formed grooves 35 in the longitudinal edge portions of a closure 4. This closure is formed at one end with a manipulating bead 5 which is offset from the plane of the closure and adapted to bear against the portion 6 of the front 40 wall of the lubricant container for a purpose to be hereinafter described. The opposite end of the closure is formed to provide a vertical tongue 7 which is curved longitudinally and which is adapted to be 45 frictionally engaged with the portion 8 in the front wall of the lubricant container, as shown in Fig. 3 of the drawing. The tongue 7 through being curved vertically, as described, is offset slightly from the plane 50 of the closure so as to coöperate with the offset portion of the bead 5 when the tongue and bead are frictionally engaged with the front wall of the lubricant container so as

to cause the guide flanges 3 to be securely retained in the guide grooves of the closure. 55 This construction is also such that the opening 2 in the lubricant container will be entirely closed so as to prevent the entrance of foreign matter into the container.

The container is provided with a vertical 60 series of partitions 9 which extend upwardly from the bottom of the container and which are suitably spaced from each other so that the container is divided on its bottom into a plurality of compartments 10. Each compartment is provided with a discharge nipple 11, the upper end of the nipple being disposed above the plane of the bottom of the container and the lower end of the nipple being extended below the plane of the 70 bottom, as shown. This construction is such that the lower end of the nipple may be fitted to a suitable conveying tube, (not shown), whereby the lubricant can be conveyed from the container to the object to 75 be lubricated. By extending the upper ends of the nipples above the plane of the bottom of the container the sediment in the lubricant will be held against being discharged into the nipple and will be retained on the 80 bottom of the container. To further protect against oil or foreign matter being conveyed with the lubricant to the object to be lubricated I provide in each compartment a relatively large absorbent member 12 which 85 may be raw cotton, felt or any other suitable material which will operate to absorb the lubricant and permit the same to be fed to the conveying tube. Each absorbent member is formed with a depending reduced 90 portion which extends into the nipple.

The device is extremely simple in construction and is particularly desirable for use upon threshing machines or the like, hence the provision of means for preventing 95 the accumulation of dust or foreign matter in the lubricator and the provision of a plurality of feed nipples, the object being to so arrange the nipples that they may be attached to a corresponding number of conveying tubes, which latter may be led to the various portions of the machine to be lubricated.

I claim:—

A lubricator comprising a box having oil 105 discharging means, one of the said walls of

the box being provided with an opening, the edges of the wall above and below said openings being formed U-shaped and disposed in opposite directions, and a cover 5 having U-shaped edge portions snugly interlocking with the U-shaped edge portions of the box and having a longitudinal end tongue concaved inwardly to engage the box

and hold said cover against accidental sliding.

In testimony whereof I affix my signature in presence of two witnesses.

HENRY C. NOFFSINGER.
